UNITED STATES PATENT OFFICE

WILLIAM J. PHELPS, OF WEST HARTFORD, CONNECTICUT

APPARATUS FOR OPERATING DOORS

Application filed March 19, 1930. Serial No. 437,228.

This invention relates to improvements in apparatus for operating doors and is directed more particularly to apparatus for opening and closing the swinging doors of garages and the like.

The principal object of the invention is the provision of apparatus which is adapted to be operated at a location remote from the doors. For instance, the driver of a vehicle entering or leaving a garage may, without leaving the vehicle, grasp certain operating devices and cause the apparatus to either open or close a door or doors.

The apparatus is simple in construction and efficient in operation and of such a nature that it may be used for operating swinging doors in general.

Various novel features and advantages of the invention will be observed from the following description of the preferred form thereof. It will be understood that various changes may be made in the form of the invention without departing from the spirit and scope thereof.

In the drawings:

Fig. 1 is a sectional plan view through the walls of a building such as a garage having the apparatus of the invention associated therewith; and

Fig. 2 is an elevational sectional view through a building showing the apparatus in another plane.

Referring to the drawings the invention will now be described in detail.

A garage building is shown as comprising side walls 2 and an end wall 4. A floor 6 in the building may be of concrete and a runway 8 may extend from the forward side thereof.

A pair of doors 10 are hinged as at 12 to the side walls 2 for swinging movements between a closed position shown in full lines and an open position shown in dotted lines. It is to move the doors between these positions that the apparatus of the invention relates.

A pair of links 14 have their outer ends pivotally connected to brackets 16 fixed to the doors adjacent the hinges 12 as shown. The inner ends of the links are pivoted at 18

to the outer end of a longitudinal operating bar 20. The inner end of bar 20 is pivotally connected at 21 to one end of a knuckle bar 22, the other end of which is pivotally connected to a bracket 24 fixed on the rear wall 4 of the building.

The bars are so proportioned and connected that as they move from the full line to the dotted line position they force their doors from their closed to their open position. As they move in a reverse direction, they function to close the doors.

A support 26 fixed to the garage structure has a hook 28 pivoted thereto, the lower end of which is adapted to engage the pivot 21 so as to hold the bars in their upper position. A tension spring 30 connected between the upper end of hook 28 and a pin 32 of said support urges the hook into the latching engagement with the pivot, as shown.

A weight 34 on one of the bars such as 20 is provided to cause the bars to descend when the pivot is released by the hook.

A housing 36 located outside the building has a lever 38 pivoted therein and receives one end of a conduit 40 which extends into the building.

A cable 42 connected at one end to the weight 34 or to one of the bars is guided over pulleys 44 and 46 and extends through conduit so that its other end is connected to the lower end of lever 38.

By swinging the lever to the left, when the bars are in a lower position, the cable is caused to elevate the bars so that they are latched in an upper position by the hook.

A similar cable 50 having one end secured to the upper end of hook 28 is guided by suitable pulleys 52 and 54 and extends through conduit and has a free end 56 outside the housing as shown.

By grasping the free end and pulling it the hook is swung to release the pivot member 21 and the weight causes the bars to descend, to spread the links and open the doors.

With the doors closed as a vehicle is brought to a stop adjacent the housing, an operator may reach for the free end 56 of cable 50. By pulling this cable the hook 28 is moved to release the pivot whereby the bars

assisted by the weight descend to force the doors to an open position.

As a vehicle is driven out of the garage an operator may, when the vehicle is brought to a stop position adjacent the housing, grasp the lever and swing it so as to elevate the bars and close the doors in which position they are held by the hook which engages the pivot pin 21.

10 It may be desirable to attach auxiliary cable operating members to the cable at points near the corner of the building. These may be grasped by a person at that place without the necessity of going over to the housing.

15 It will be observed that the apparatus operates between a contracted and expanded position and functions in the nature of a wedge to move the doors outwardly.

The structure may be varied within wide 20 limits without departing from the spirit and scope of the invention, and therefore I prefer to be limited, if at all, by the appended claims rather than by the foregoing description.

25 What I claim is:

1. The combination of a pair of doors hinged at opposite forward corners of a building and a fixed support disposed adjacent a rear part of said building with apparatus for operating said doors comprising, links connected at outer ends to said doors, a bar connected at its forward end to inner ends of said links, a knuckle bar connected to the rear end of the other bar and to said support, the said bars being proportioned so that they assume an angular position when the doors are closed and are adapted to move to a position of relatively greater angularity to open said doors, a spring operated latch to open said doors, a spring operated latch 30 for engaging and holding said bars in the first named angular position and means acting on said bars to assist them in assuming the last-named position.

2. The combination of a pair of doors hinged at opposite forward corners of a building and a fixed support disposed adjacent a rear part of said building with apparatus for operating said doors comprising, links connected at outer ends to said doors, a bar connected at its forward end to inner ends of said links, a knuckle bar connected to the rear end of the other bar and to said support, the said bars being proportioned so that they assume an angular position 40 when the doors are closed and are adapted to move to a position of relatively greater angularity to open said doors, a spring operated latch for engaging and holding said bars in the first-named angular position and means acting on said bars to assist them in assuming the last-named position and means for manually disengaging said latch.

3. The combination of a pair of doors hinged at opposite forward corners of a building and a fixed support disposed adja-

cent a rear part of said building with apparatus for operating said doors comprising, links connected at outer ends to said doors, a bar connected at its forward end to inner ends of said links, a knuckle bar connected to the rear end of the other bar and to said support, the said bars being proportioned so that they assume an angular position when the doors are closed and are adapted to move to a position of relatively greater angularity to open said doors, a housing removed from said building having an operating member movable therein, connections between said lever and said bars whereby the bars may be moved from the last-named to the first-named position.

4. The combination of a pair of doors hinged at opposite forward corners of a building and a fixed support disposed adjacent a rear part of said building with apparatus for operating said doors comprising, links connected at outer ends to said doors, a bar connected at its forward end to inner ends of said links, a knuckle bar connected to the rear end of the other bar and to said support, the said bars being proportioned so that they assume an angular position when the doors are closed and are adapted to move to a position of relatively greater angularity to open said doors, a housing removed from said building having an operating member movable therein, connections between said lever and said bars whereby the bars may be moved from the last-named to the first-named position and connections between said housing and said latch whereby the latch may be operated from the housing.

5. The combination of a pair of doors hinged to opposite forward parts of a building and a fixed support spaced rearwardly from said parts and doors with apparatus for operating said doors comprising, links connected at their outer ends to said doors, a bar connected at its forward end to the inner ends of said links, a knuckle bar connected to the rear end of said first-named bar and to said support, the said bars and links being arranged for relative swinging movements and proportioned to assume increasing angular positions as the doors are swung from closed to open position and adapted to urge the doors from closed to open position and releasable locking means for engaging and holding said bars in a certain angular position to lock said doors against opening movements.

6. The combination of a pair of doors hinged to opposite forward parts of a building and a fixed support spaced rearwardly from said parts and doors with apparatus for operating said doors comprising, a bar and connections between the forward end thereof and said doors, a knuckle bar pivotally connected at one end to said support and at its other end to the rear end of said

first-named bar, the said bars being supported by the connections between said doors and said support and arranged for relative swinging movements in vertical planes and proportioned so that they assume an angular position when the doors are closed and are adapted to move to a position of greater angularity to open said doors, a releasable latch for engaging and holding said bars in the first-named angular position and means for disengaging said latch whereby the bars may move to said position of greater angularity to open said doors.

In testimony whereof I affix my signature.

WILLIAM J. PHELPS.
